UNITED STATES PATENT OFFICE

AUGUST D. EITZEN, OF NEW YORK, N. Y., ASSIGNOR TO NEWS PROJECTION CORPORATION, OF NEW YORK, N. Y., A CORPORATION OF NEW YORK

TICKER PROTECTING MEANS

Application filed February 7, 1929. Serial No. 338,064.

This invention relates to news printing tickers such as stock quotation tickers in general, and especially to stock quotation projecting machines.

- 5 When news printing machines such as tickers and the like are used with wind-up reels for winding up the tape as it is delivered by the ticker, or with stock quotation projecting machines where the tape is pulled through
 10 the projecting machine as it is delivered from the ticker, care must be exercised that the pull transmitted to the tape as it is delivered from the ticker is properly controlled so that the delicate mechanism of the ticker is not
 15 upset. In practice it has been found that if this pull is not properly controlled, a slight excess will be sufficient to disturb the proper alinement of the delicate parts of the ticker so that the type will not only print out of
 20 alinement but also print the wrong letter.

To this end it is one of the main objects of the present invention to provide means whereby the delicate mechanism of the ticker is positively protected from any such excessive pull.

These and other features, capabilities and advantages of the invention will appear from the subjoined detail description of one embodiment thereof, illustrated in the accompanying drawings in which

Figure 1 illustrates a ticker in outline equipped with the ticker protecting means;

Fig. 2 is a fragmental section on the line 2—2 of Fig. 1; and

Fig. 3 illustrates diagrammatically a tape puller and ticker associated with the ticker protecting means.

In the embodiment illustrated, the outline of a ticker 1 is shown in dash and dot lines having the stop plate or frame member 2 provided with the usual tape discharging plate 3. In the present instance, this tape discharging plate 3 is provided with a recess at 4 nearest the front end 5 of the discharging plate 3. The tape T as it leaves the printing mechanism of the ticker 1 passes in the direction of the arrows 6, 6, to the discharging plate 3. Above the plate 3 there is secured a pin 7 to which is pivotally secured the lever 8 having a short rear arm 9 and a long front

arm 10 terminating in a downwardly extending finger portion 11 registering with the recess 4 in the discharging plate 3. The short arm 9 is substantially one-fifth the length of the long arm 10 although the relative lengths of these arms will of course be determined according to the pressure to be exercised on the tape T by means of the end of the finger 11.

As shown in Fig. 1, it will appear that when the tape T is being advanced by the ticker 1 to form a slack in front of the finger 11, such slack will be sufficient to permit the contact end of the short arm 9 to clear the tape T and permit a tape puller P freely to pull the tape until such slack has been taken up. It will also appear that as soon as this slack has been taken up and the ticker 1 comes to rest, the tension on the tape T by the tape puller P in the direction of the arrow 6, 6, will take up the slack in the tape T to engage the finger 11 of the lever 8 to raise the arm 10 and thereby depress the arm 9 and in turn cause the tape T at the point 12 to be tightly held between the end of the arm 9 and the discharging plate 3. Due to the increased length of the arm 10 as compared to the arm 9, this pressure will be sufficiently multiplied positively to anchor the tape T from being advanced by the tape puller P. In fact the relative lengths of the arms 10 and 9 are preferably such that the pressure exercised by the arm 9 will prevent the pulling of the tape T except by tearing or rupturing the tape T at the point 12. When the proportions are so adjusted, the delicate mechanism of the ticker 1 will of course be positively protected from injury by any excess tension exercised by the tape puller P.

It will also appear that the tape puller P will cooperate with the lever 8 to maintain the tape T taut in the projector R when the ticker is at rest and thus insure a smooth and even projection of the printed matter on the tape.

It is obvious that various changes and modifications may be made to the details of construction without departing from the general spirit of the invention as set forth in the appended claims.

I claim:

1. The combination with a ticker, of a tape puller for taking up the slack in the tape as it is delivered by the ticker, and means normally out of tension exercising position when slack is formed in the tape and operable for exercising tension on the tape as soon as the slack has been taken up to protect the ticker against injury.
- 10 2. The combination with a ticker, of a tape puller for taking up the tape as it is discharged by said ticker, and a lever normally riding freely on the tape and operable for exercising pressure on the tape when the slack has been taken up in the tape by said tape puller to protect the ticker from excessive pulling tension.
- 20 3. The combination with a ticker, of a tape puller for taking up the slack in the tape as the tape is discharged by said ticker, an abutment, and a lever having a short arm and a long arm both adapted to engage the tape, the long arm cooperating with the tape to cause the short arm to impinge the tape against said abutment when the slack in the tape has been taken up by said tape puller.
- 30 4. The combination with a ticker, of a tape puller for drawing the tape as it is discharged by said ticker, an abutment, and a lever having two arms adapted to engage the tape, the tension in the tape cooperating with one of said arms to cause the other of said arms to impinge the tape against said abutment when the slack in the tape has been taken up by said tape puller.
- 40 5. The combination with a ticker, of a tape puller, a discharge plate having a recess across which the tape passes as it is discharged by said ticker, and a lever having a short arm and a long arm both adapted to engage the tape, the long arm registering with said recess and being operative to cause said short arm to impinge the tape against said discharge plate when the slack in the tape has been taken up by said tape puller to raise the tape out of said recess and thereby actuate said long arm.

AUGUST D. EITZEN.
